UNITED STATES PATENT OFFICE.

JOHN MARTIN AND JOSIAH MERRILL, OF GREAT FALLS, NEW HAMPSHIRE.

LAST.

SPECIFICATION forming part of Letters Patent No. 241,684, dated May 17, 1881.

Application filed January 25, 1881. (Model.)

To all whom it may concern:

Be it known that we, JOHN MARTIN and JOSIAH MERRILL, of Great Falls, in the county of Strafford and State of New Hampshire, have 5 invented a new and useful Improvement in Lasts, of which the following is a specification.

Our invention relates to lasts for the manufacture of boots and shoes, and it has for its object the production of an improved and durable last, and one which can be changed to suit the style at a small cost.

In the accompanying drawings, Figure 1 is a plan view, partly in section. Fig. 2 is a bottom view, and Fig. 3 is a cross-section taken 15 on the line $x x$ of Fig. 2.

Similar letters of reference indicate corresponding parts.

A represents the wood portion of the last, the bottom of which is formed with the side 20 grooves, $a a$, extending along the instep and ball, and with the studs or projections $b b$. The metallic bottom B is formed with the slots $c c$ and the side ribs, $d d$, which extend along the instep and ball of the last, and with the openings $e e$, which fit over the studs $b b$ of the wood portion, the side ribs fitting in the side 25 grooves, $a a$, thereof.

The metallic bottom may be of cast-iron or other cast metal, or it may be stamped into 30 shape from sheet metal or swaged in dies, and when formed by any process is to be leaded or otherwise firmly secured to the wood portion.

It is obvious that, instead of forming the wood portion with studs or pins and the metallic portion with holes, this might be reversed by forming the bottom with pins and the wood portion with holes, and accomplish the same result; or the pins and holes might be omitted altogether, the side ribs serving as sufficient stays; but the plan shown and described is preferred.

We are aware that it is not new to make a last of a metallic body recessed between its heel and toe to receive a wooden block having plug-recesses and provided with longitudinal grooves on its lower part, or to hold a metallic plate by tubes on the plate, screw-sleeves, and bolts, or to use on a wooden body a metallic toe and heel connected by edge strips; but

What we claim as new and of our invention is—

A boot or shoe last consisting of the upper wooden portion, A, and the bottom metallic portion, B, the portion A provided with the side grooves, $a a$, and studs $b b$, and the portion B provided with the slots $c c$, side ribs, $d d$, and bottom openings, $e e$, as shown and described.

JOHN MARTIN.
JOSIAH MERRILL.
